BENDING MACHINE

Ralph M. Shaw, Jr., Edgewater Park, N. J., assignor to Pedrick Tool & Machine Company, Philadelphia, Pa., a corporation of Pennsylvania

Application October 9, 1943, Serial No. 505,634

16 Claims. (Cl. 153—46)

1

This invention relates to machines useful more particularly in bending metallic structural bars or rods of different cross section, pipes, tubes, etc., and has reference more specifically to bending machines of the table type such as disclosed in U. S. Patent No. 2,266,912, granted to me on December 23, 1941.

The chief aim of my present invention is to enhance the utility of bending machines of the kind referred to, i. e., to enable formation of complex and irregular bends of different radii in one operation, as well as circular bends of different constant radii, without necessitating die interchanges or substitutions of other parts of such machines.

Another object of this invention is to effect the bending of bars and the like mainly by compressive action, and substantially without any deformation of the original cross-section.

How the foregoing and other objects and advantages are readily realized in practice will appear from the following detailed description of the accompanying drawings, wherein

Fig. 1 is a fragmentary view in plan of one embodiment of my improved bending machine.

Figs. 2, 3 and 4 are fragmentary sectional views taken as indicated respectively by the angled arrows II—II, III—III and IV—IV in Fig. 1.

Fig. 5 is a view corresponding to Fig. 1, showing an alternative embodiment of my invention; and

Figs. 6, 7 and 8 are diagrammatic views in top plan showing how complex bends of changing curvature can be made with a machine of my invention.

With reference first more especially to Figs. 1—4, the bending machine there shown comprises a circular bed 10 which is recessed for flush reception of a turn-table in the form of a disk 11 having peripheral teeth 12 in meshing engagement with a driving pinion 13 journaled in said bed. Suitably fixed in the bed 10 is a stud or post 14 which extends upwardly through a central aperture in the turn-table 11. Fulcrumed on the stud or post 14 is an arm 15 which reaches to the marginal surface of the bed 10 where it is fixable against turning about said stud by a removable latch pin 16 which is selectively engageable with socket apertures at intervals circumferentially of said bed. As shown, the arm 15 has a longitudinally-extending dove-tail slot 17 along which a block 18 is adjustable by means of a screw spindle 19. Incorporated with the block 18 is a holding means in the form of a quick-releasable manually-operable clamp 20 by which a flat bar B of rectangular cross section which is to be bent is se-

2
cured in the machine. Also fulcrumed on the stud or post 14 and arranged at opposite sides of the clamp arm 15 are arms 22 and 22a which are right and left counterparts of each other. The arm 22 has parallel longitudinally-extending dove-tail slots 23 and 24 for guidance of blocks 25 and 26 which are adjustable along said slots by screw spindles 27 and 28 respectively. Mounted on the block 25 is a vertical axis grooved roller 31 which is adapted to engage one side edge of the bar B; while a pair of similar grooved rollers 32 and 33 are freely rotatable respectively about studs 34 and 35 upstanding from the block 26, engage the other side edge of the bar B. It is to be noted that, when in operative position, the rollers 31 and 32 engage the bar B at diagonally opposite points, while the roller 32 is laterally spaced at a fixed distance from the roller 31 in a plane at right angles to the arm 22. At its outer end the arm 22 has an apertured lug projection 36 for passage of a latch pin 37 whereby it may be secured to the turn-table 11 for movement by the latter about the stud 14. For the purpose of positively driving the roller 31, during certain bending operations, there is provided a variable speed electric motor 38 which is fixedly supported by the block 25 and which has a miter gear pinion 39 on its shaft in mesh with a companion miter pinion 40 affixed to said roller. The arm 22a is equipped with a group of grooved instrumentalities which are identical with those above described in connection with the arm 22 but reversely arranged, the corresponding parts being identified by the same reference numerals with the letter a added in each instance for convenience of more ready distinction. For operation upon a bar B of flat rectangular cross section such as the one illustrated, the rollers 31, 31a and 32, 32a are configured as instanced in Fig. 4, i. e., provided with circumferential grooves of rectangular profile to correspond accurately with the cross section of said bar.

In preparation for the bending, the rollers 31 and 31a are adjusted along the arms 22 and 22a relative to the axis stud or post 14 of the machine by means of the screw spindles 27 and 27a in accordance with the radius of the curvature desired, whereupon the clamp block 18 is shifted inward along its arm 15 by means of the screw spindle 19 to bring the inner edge of the bar B into the grooves of said rollers 31 and 31a. The blocks 25 and 26a are next shifted inwardly along the arms 22 and 22a respectively by means of the adjusting screws 28, 28a to bring the rollers 32, 32a and 33, 33a into engagement with the outer

edge of the bar B. With the parts thus set, the roller arm 22a free, the clamp arm 15 secured against rotation by the latch pin 16 and the roller arm 22 locked to the turn-table 11 by the latch pin 37, said table is rotated in the direction of the curved arrow in Fig. 1. As the arm 22 moves with the turn-table 11 for example to the position in which it is shown in dot-and-dash lines, the end portion of the bar B below the clamp arm 15 as viewed in Fig. 1 is bent at X by the cooperative action of the grooved rollers 31 and 32, the roller 33 serving to keep said bar confined to its original plane. For a short bend, the roller 31 may be allowed to roll freely through traction with the inner edge of the bar B. However, for larger bends up to a semi-circle, the roller 31 is positively driven in the direction of the arrow thereon by the motor 38 at a speed somewhat faster than it would ordinarily rotate by traction with the bar B so as to effect a smoothing of the metal of said bar and thereby prevent flattening of the bend as the roller arm 22 continues its movement in the direction of the curved arrow in Fig. 1 beyond the dash-and-dotted line position. The other end portion of the bar B can obviously be bent in a like manner until a complete circle is formed. In preparation for the latter bending step, the latch pin 37 is withdrawn to free the arm 22 and used to lock the arm 22a to the turn-table 11 which is thereupon rotated in the direction opposite to that indicated by the curved arrow in Fig. 1.

The radius of the bend in all cases is determined by the distance of the rollers 31 and 31a from the axis of the machine and not on the distance of the rollers 32 and 33 from the rollers 32a and 33a, and is independent of the dimensions of any of said rollers. The spacing of the rollers 32, 33 and 32a, 33a is for the purpose of changing the leverage, thereby to minimize flattening and wrinkling of the work or bar B as it is being bent, the rollers 33 and 33a serving to convert the single fixed loading of each of the rollers 32 and 33a into uniform distributed load. The machine thus differs from the usual forms of roller benders since the arrangement of the roller assemblies is non-pyramidal. The use of two arms 22, 22a as herein shown is especially advantageous in that it allows bends to be made in different planes. By suitably shaping the jaws of the holder clamp 20 and the peripheries of the grooved rollers 31—33 and 31a—33a, the machine can of course be adapted to bending bars of cross-sectional shapes other than the one herein shown by way of example.

By reference once more to Fig. 1, it will be noted that the elements 31 and 31a function as progressively moving die points with the elements 26, 33 and 26a, 33a constituting correspondingly moving points of application of the forces by which the bar B is pressed toward the elements 31 and 31a, and moreover that the bending force or torque of the machine transmitted to the elements 26, 33 and 26a, 33a operates against a leverage arm equal to the distance between the axes of the elements 26, 26a and the elements 31, 31a respectively. The bending is therefore accomplished by compression rather than by tension, with the neutral axis of the bar B lying outside of the center of gravity. In other words as the bending is progressively effected by coaction between the moving groups of elements 26, 31, 33 and 26a, 31a, 33a, the bulk of the bar B is subjected to compression without any substantial attendant tensioning of the outside portions of the

bends. Accordingly, under these circumstances the bending is accomplished with little or no change in the cross section of the bar from its original form and dimensions.

The alternative embodiment of my improved bending machine illustrated in Fig. 5 is generally similar to that of Figs. 1-4, having two arms 22c and 22d respectively with grooved rollers 31c, 32c, 33c and 31d, 32d, 33d, but being devoid of the clamp arm 15. Another difference to be noted is that the end lugs 36c and 36d of the arms are each provided with two apertures so that they may be locked either to the machine bed 10c or to the turn-table 11c by means of the latch pins 37c, 37d for the reception of which said bed and said table are respectively provided at suitably spaced circumferential intervals with socket holes 43 and 44. It will be further noted that here, the adjusting screws 27c, 27d and 28c, 28d have secured to them spur gear pinions 45c, 46c and 45d, 46d respectively with which idler pinions 47c and 47d slide on studs 48c and 48d at the outer ends of the roller arms 22c and 22d are meshed at certain times for a purpose presently explained. All other elements in the alternative embodiment not specifically referred to but having their counterparts in the first embodiment are, in order to preclude the necessity for repetitive description, identified by the same numerals but differentiated by use with them of the letters c and d.

The procedure followed in making bends of changing curvature in one operation in the alternative machine of Fig. 5 is as follows: In preparation, the arm 22d is secured against rotation to the machine bed 10c by the latch pin 37d, with the arm 22c positioned alongside it and secured to the table 11c by the latch pin 37c. The rollers 31c and 31d are next adjusted to the desired positions along the arms 22c and 22d; the bar B engaged with said rollers; the rollers 32c, 33c and 32d, 33d are then moved inward of said arms to engage the outer edge of said bar, and the spur pinion 47c shifted into mesh with pinions 45c and 47c on the spindles 27c, 28c of the arm 22c. All being now in readiness with the bar B held by the rollers of arm 22d, the table 11c is rotated in the direction of the curved arrow in Fig. 5 through a distance say of ninety degrees, whereby the arm 22c is moved to the position in which it is shown in Fig. 6 to form the bend X' in the bar B, after which said arm is latched to the bed 10c. With this accomplished, the arm 22d is pinned to the bed 10c as likewise shown in Fig. 6 and moved to the position in which it is shown in dot-and-dash lines in the last mentioned figure by further rotation of the bed in the same direction as before, and finally re-latched to the bed 10c to hold the bar B at the terminus of the bend X' just completed. The arm 22c is thereupon again latched to the table 11c and the latter further turned still in the same direction to move the arm 22c say to the position in which it is shown in Fig. 7 and then latched to the bed 10c and the arm 22d latched to the table 11c. The table 11c is then turned still further in the same direction to bring the arm 22d alongside the arm 22c and thereafter latched to the bed 10c to hold the bar B at the terminus of the now completed second portion X² of the bend. Thereupon the arm 22c is re-latched to the turn-table 11c, and the latter turned still further in the same direction to bring said arm to the position say in which it is shown in Fig. 8, the rollers 31c, 32c and 33c being

incidentally moved inward of the arm 22c progressively by turning of one of the spindles 27c and 28c (the other spindle being obliged to follow suit by reason of being connected by the gears 45c, 46c and 41c), with the result that a sharper curve is formed in the bar B as shown at X³ in Fig. 8. These settings and operations are repeated as often as necessary depending upon the shaping desired in the bar B; and it is to be understood that, by like manipulations and selective use of the two arms 22c, 22d, the other end portion of the bar may be similarly or differently bent through curvatures of changing radii.

To facilitate complex bending operations of the kind just described, I provide templates such as the one shown at 50 in Figs. 6-8 to define the lines along which the bends are to be made. The template 50 may be in the form of a suitably profiled plate capable of being removably secured against rotation in the machine to the top of the stud 14c above the roller arms 22c and 22d. It is of course within the province of my invention to substitute power means for actuating the spindles of the arms 22c and 22d in lieu of the hand wheels herein shown by way of example.

Having thus described my invention, I claim:

1. In a machine for bending bar and the like, an arm movable about a fixed fulcrum; more than two rollers supported by the arm to one side of said fulcrum and relatively adjustable directly along said arm to engage opposite sides of the bar at diagonally related points, as considered with respect to the fulcrum, with one of said rollers serving as a backing means beyond the others and also to confine the bar to its original plane; quick-release holder means for fixedly supporting the bar during the bending operation; and means operatively-coordinated with one of the rollers aforesaid for moving the arm about its fulcrum relative to said holder means.

2. A bending machine according to claim 1, further including means whereby the spaced rollers can be simultaneously adjusted along the supporting arm; and means whereby the bar holder means can be correspondingly adjusted radially of the fulcrum of said arm.

3. A bending machine according to claim 1, wherein the roller supporting arm rotatively includes a pair of longitudinally-extending adjusting screw spindles; wherein followers on the said screw spindles respectively carry an individual and plural rollers; and further including means whereby the bar holder can be adjusted radially of the fulcrum of the arm to correspond with adjustments of the spaced rollers.

4. A bending machine according to claim 1, further including a backing means for contacting one side of the bar at a point beyond one of the spaced rollers transversely of the supporting arm; means whereby a pair of the rollers together with the associated backing means, can be independently or simultaneously adjusted along the supporting arm; and means whereby the holder means can be correspondingly adjusted radially of the fulcrum of the supporting arm.

5. A bending machine according to claim 1, wherein a variable speed motor is provided to drive one of the spaced rollers in the direction it would naturally turn by traction with the bar during the bending operation.

6. A bending machine according to claim 1, wherein a variable speed motor is provided to drive the spaced roller which engages the inner side of the bar in the direction it would natural-

ly turn by traction with said bar during the bending.

7. In a machine for bending bars and the like, a bed; a fixed stud upstanding from said bed; a peripherally-toothed turn-table with means whereby it is rotatable about said stud; an arm fulcrumed on the stud and carrying more than two rollers set to engage the outer and the inner sides of the bar at diagonally related points; another arm with means thereon for holding the bar during the bending operation; means whereby the first mentioned arm can be releasably secured to the turn-table for rotation thereby; and means whereby the second mentioned arm can be releasably connected in different positions around the bed beyond the periphery of the turn-table.

10 8. A bending machine according to claim 7, further including means whereby the several rollers and the holding means can be adjusted along their respective carrying arms.

15 9. In a machine for bending bars and the like, a bed; a fixed stud upstanding from said bed; a turn-table rotatable about said stud; an arm fulcrumed on the stud and having means thereon for holding the bar during the bending; a pair of arms independently fulcrumed for movement about the stud, and each carrying a pair of rollers set to engage the bars at diagonally opposite points, the rollers of one of the latter arms being reversely arranged with respect to those of the other arm of the pair; means whereby the holder arm can be releasably secured in different positions around the bed beyond the periphery of the turn-table; and means whereby each arm carrying a pair of rollers can be releasably secured selectively to the turn-table for individual rotation thereby relative to the holder arm.

20 10. A bending machine according to claim 9, further including means whereby the rollers, and the bar holder means can be individually adjusted along their respective supporting arms.

25 11. In a machine for bending bars and the like, a bed; a stud upstanding from the bed; a circumferentially-toothed turn-table with gear means whereby it is rotatable about said stud; a pair of arms fulcrumed for independent movement about the stud, each said arm carrying bending instrumentalities for engaging the bar from opposite sides at diagonally opposite points; 30 and means whereby said arms can be selectively coupled either to the bed or with the turn-table so that one may be employed as a fixed holder for the bar while the other is moved to effect the bending.

35 12. In a machine for bending bars and the like, a bed; a stud upstanding from the bed; a turn-table rotatable about said stud; an arm fulcrumed on the stud, said arm carrying a pair of rollers set to engage the outer and inner sides of the bar at diagonally opposite points, a backing means effective to contact the outer side of the bar at a point beyond the outer of the pair of rollers and transversely of the arm; a second arm similarly fulcrumed on the stud and having rollers and a backing means like that of the first arm but reversely arranged thereon; and means whereby said arms can be selectively coupled either with the bed or the turn-table so that one may be employed as a holder for the bar while the other is moved to effect the bending.

40 13. A bending machine according to claim 12, further including means whereby the roller and the backing means assemblies can be adjusted along their respective carrying arms to vary the 45 curvature of the bending.

14. A bending machine according to claim 12, further including separate variable speed power means for rotating the inner rollers of the respective arms when they are individually employed to effect the bending operation.

15. A bending machine according to claim 12, further including a template peripherally configured in accordance with the shaping desired in the bar, said template being detachably securable to the fulcrum stud above the two arms for service as a guide in adjusting the respective roller assemblies during the bending.

16. In a machine for bending bars and the like,

5

a fixed fulcrum, a lever arm movable about the fulcrum, said arm carrying more than two circumferentially-grooved rotatable elements including one element for engaging the inner side of the bar at a single point, and the other elements for engaging the outer side of the bar at a point beyond the region of contact of the bar by the first mentioned element; means for holding the bar against displacement in the machine during the bending; means for adjusting the respective bar engaging elements along the lever arm; and means for moving the arm.

RALPH M. SHAW, JR.
